UNITED STATES PATENT OFFICE.

WILLIAM M. WHEILDON, OF ASHLAND, MASSACHUSETTS, ASSIGNOR TO EDWARD H. ANGIER, OF FRAMINGHAM, MASSACHUSETTS.

COLLAPSIBLE CONTAINER.

1,375,070.

Specification of Letters Patent. Patented Apr. 19, 1921.

Application filed January 24, 1917. Serial No. 144,270.

To all whom it may concern:

Be it known that I, WILLIAM M. WHEILDON, a citizen of the United States, and resident of Ashland, in the county of Middlesex and Commonwealth of Massachusetts, have 5 invented an Improvement in Collapsible Containers, of which the following description, in connection with the accompanying drawings, is a specification, like characters on the drawings representing like parts.

10 This invention relates to containers particularly of the type arranged to collapse or fold away into small space and the object is to provide a simple and efficient device of that nature.

15 My invention will best be understood by reference to the following description of an illustrative embodiment thereof shown in the accompanying drawings, wherein,—

20 Figure 1 is a side view of a container, adapted for use as a water bucket, in its collapsed form;

Fig. 2 is a similar view showing the device brought into position for use as a container;

25 Fig. 3 is a top plan view of Fig. 2;

Fig. 4 is a broken away view of a part of the lower corner of the container on a much larger scale; and

Fig. 5 is a section on the line 5—5 of Fig. 4.

30 Referring particularly to Fig. 1 of the drawings my container comprises a suitable flat frame desirably substantially U-shaped in form and here shown as comprising the bottom member 7 and the arms 9, which 35 may conveniently flare as shown. In the present embodiment of the invention this member is made in a single piece and may be constructed from heavy wire which will possess a certain degree of resiliency. Stretched

40 between the arms 9 of the container is a bag 11 formed from a double thickness of suitable flexible material, such as light metal, textile fabric or heavy paper. In the present embodiment of the invention I have 45 illustrated a bag formed from a composite waterproof sheet which consists of two sheets of paper secured together by an adhesive in which reinforcing textile threads 13 are embedded. The preferred manner herein illustrated of attaching the bag to the arms 9 of the frame will be more fully described hereinafter.

When the frame is in its normal undistorted position illustrated in Fig. 1, the bag 11 is adapted to lie flat or substantially so 55 between the arms 9. When, however, the frame is distorted in its own plane, as by drawing the arms 9 toward each other against the spring of the wire to the position shown in Figs. 2 and 3, fullness of the bag 60 will be provided for and the flexible sides thereof will bulge outwardly as indicated best in Fig. 3 to form a spacious receptacle. Means are provided for holding the parts in the position shown in Figs. 2 and 3 to permit 65 the container to be conveniently utilized, and such means may, as in the present instance, serve as a handle for the container. I have here shown the arms 9 as provided with integral inwardly-directed extensions 70 15 which may terminate as shown in oppositely directed hook portions 17. One of these hook portions may have a terminal projection 19 adapted to fit a corresponding recess 21 in the point of the opposite hook 75 portion. When the arms 9 are drawn together the points of the hooks oppose each other and the projection 19 will fit the recess 21 and lock the two together as shown in Fig. 2. The effective length of the two portions 15 when locked together is less than the width at its mouth of the bag 11 when spread flat, and thus the two arms 9 are held pressed 80 toward each other and fullness of the bag 11 is provided for. The extensions 15 provide 85 a handle or bail for the container and in the particular embodiment shown the hook portions 17 coöperate to form an oval hand-receiving loop.

90 By such means as described, the bag is held in the position shown in Figs. 2 and 3 and may conveniently be carried about. The bottom part 7 of the frame forms a grip by which the container may be tilted, for example, to pour from it or to dip with it.

95 I have here shown a rod 23 pivotally secured by a rivet 25 to the bottom member 7 of the frame and, as shown in Fig. 1, adapted to lie in the same plane. When the container is brought to the position of Figs. 2 100 and 3, the rod 23 may be turned on the pivot 25 to a position transverse to the member 7, thus forming an extended bottom on which the bucket may stand.

In the present embodiment of the invention I have shown the bag member 11 as being, independently of its connection with arms 9, a complete bag closed at the sides 5 as well as at the bottom. The bag, whether or no so constructed can be secured to the side arms 9 in any convenient manner, but preferably as illustrated. As best seen in Figs. 4 and 5, the edge of the bag 11 is 10 wrapped about an arm 9 and clamped thereto, conveniently by means of a channeled spring member 27 having the sectional form clearly shown in Fig. 5 and somewhat similar to the Greek capital letter omega. This 15 channeled member embraces both the arm 9 and the edges of the bag, and clamps the latter about the former. The structure may be such that the member 27 may be slid longitudinally from the member 9 to release 20 the bag 11. The frame may be flattened or reduced slightly as shown at 29 to enter the restricted mouth of member 27 and thus permit the application thereof. By such means the latter may readily be removed. For ex- 25 ample, the frame may be supplied with a number of bags of some cheap material such as paper, and the user can place a new bag in position in the frame whenever he desires.

A container such as that described is 30 readily and cheaply made, may be stored away in small space when collapsed and conveniently distended for use. When distended it is of stable form and its frame renders it easy to handle. I have herein described a 35 single embodiment in detail but it will be understood that the construction may be widely varied without departing from the principles of the invention.

What I claim and desire to secure by Letters Patent is:

1. A collapsible, unitary, individually portable container comprising a resilient frame substantially of U-shape, a flexible bag extending between the arms thereof, and means to hold said arms abnormally 45 pressed toward one another to provide for fullness of the bag, said means extending across the mouth of the bag and constituting a bail-like handle for the container.

2. A collapsible container comprising a resilient frame substantially of U-shape, a flexible bag extending between the arms thereof, said arms having in-turned portions opposite the base of said frame providing 55 means to hold said arms abnormally pressed toward one another to provide for fullness of the bag.

3. A collapsible container comprising a resilient frame substantially of U-shape, a 60 flexible bag extending between the arms thereof, said arms having in-turned portions opposite the base of said frame provided with terminal hook portions, the points of which are adapted to be interlocked thereby 65 both to hold said arms abnormally pressed

toward one another to provide for fullness of the bag and also to present a hand-receiving loop.

4. A collapsible, unitary, individually portable container comprising a substantially 70 U-shaped frame, a flexible bag between the arms thereof, and means for holding said arms together to provide for fullness of the bag, said means extending across the mouth of the bag and providing a bail-like 75 handle for the container.

5. A collapsible, unitary, individually portable container comprising a flexible, open-topped bag, stiff supporting bars extending along the edges of the bag substantially 80 throughout the length thereof and secured thereto and shiftable means for connecting said bars across the mouth of the bag in connecting position providing a substantially rigid bail-like handle of less 85 length than the width of the mouth of the bag when spread flat, which handle determinately spaces said bars to provide in said bag a fullness furnishing a receptacle.

6. A collapsible, unitary, individually 90 portable container comprising a flexible, open-topped bag, stiff supporting bars extending along the edges of the bag substantially 95 throughout the length thereof and secured thereto, said bars having inturned extensions adjacent the mouth of the bag arranged to interlock and having an effective length less than the width at its mouth of the bag when spread flat.

7. A unitary, individually portable container comprising a substantially plane frame having opposed side portions and opposed top and bottom portions, a flexible bag extending between said side portions, said frame being distortable in its plane and having a position in which said top portion provides a bail-like handle and in which said bag has a fullness furnishing a receptacle and having provision whereby it may be held in such position.

8. A container comprising a substantially plane frame having opposed side portions and opposed top and bottom portions, a flexible bag extending between said side portions, said frame being distortable in its plane and having a position in which said top portion provides a bail-like handle and in which said bag has a fullness furnishing a receptacle, and having provision whereby it may be held in such position, said side 115 portions embodying in their structure channeled clamps embracing the edges of the bag.

9. A collapsible container comprising a frame having opposed side portions, a flexible bag adapted to extend between the arms 125 of the same, clamps of channeled section having restricted mouths, said clamps being adapted to embrace said side portions and the edges of the bag, and said frame having reduced portions adapted to enter 130

the mouths of said clamp to facilitate the application thereof.

10. A collapsible, unitary, individually portable container comprising an open-
5 topped bag and a frame including side bars secured to the sides of said bag and a connection adapted to extend bail-like therebetween across the mouth of said bag, said

frame being resilient and normally holding said bag extended flat between said arms, 10
said connection providing means for holding said bars abnormally pressed together to provide fullness in the bag.

In testimony whereof, I have signed my name to this specification.

WILLIAM M. WHEILDON.
